INFANT'S GARMENT

Victor R. Del Guercio, Larchmont, N. Y.

Application June 23, 1953, Serial No. 363,473

4 Claims. (Cl. 128—287)

The present invention relates to an infant's garment, and more particularly to a panty-designed diaper cover.

An object of the present invention is to provide an infant's diaper pants so constructed and designed to be worn over diapers so that the urine which penetrates the diaper will not penetrate the infant's pants.

A further object is to provide an infant's diaper pants which may ultimately be employed as a training pants, or as a training pants cover once the water repellency of the garment is completely reduced, which is efficient in operation and easy to manufacture.

Yet another object is to provide an infant's diaper pants provided with shirt tabs which permit the attachment of the said pants to the infant's shirt in such a manner that there is no possibility of the infant's urine working its way by osmosis to the infant's shirt.

Another object of the present invention is to provide an infant's pants comprising, a one-piece outer layer of water repellent cloth, said outer layer of water repellent cloth consisting of a waist portion provided with an elastic band, side portions, and a crotch portion with oppositely disposed leg cut-out portions; an inner layer of water repellent material to provide a second crotch portion similar in size and shape to said first mentioned crotch portion; an intermediate layer of difficult to stretch water repellent material to provide a third crotch portion similar in size and shape to said above mentioned crotch portions, said crotch portions being joined together by stitching, and a shirt tab secured to each of said side portions.

A further object of the present invention is to provide an infant's pants comprising, a one-piece outer layer of water repellent cloth, said outer layer of water repellent cloth consisting of a waist portion provided with an elastic band, side portions, and a crotch portion with oppositely disposed leg cutout portions; an inner layer of water repellent material to provide a second crotch portion similar in size and shape to said first mentioned crotch portion; an intermediate layer of difficult to stretch water repellent material to provide a third crotch portion similar in size and shape to said above mentioned crotch portions, said crotch portions being joined together by stitching, each of said crotch portions including a narrow area and two fan-shaped areas each extending therefrom to have a portion thereof terminate at a point approximately three-fourths of the distance from the midpoint of the said narrow area to the said elastic band, and a shirt tab secured to each of said side portions near said elastic band in said waist portion.

Still another object of the present invention is to provide an infant's pants comprising, a one-piece outer layer of water repellent knit cotton, said outer layer of water repellent knit cotton consisting of a waist portion provided with an elastic band, side portions, and a crotch portion with oppositely disposed leg cut-out portions; an inner layer of water repellent knit cotton to provide a second crotch portion similar in size and shape to said first mentioned crotch portion; an intermediate layer of flannelette cotton material treated with a water repellent composition to provide a third crotch portion similar in size and shape to said above mentioned crotch portions, said crotch portions being joined together by stitching, each of said crotch portions including a narrow area and two fan-shaped areas each extending therefrom to have a portion thereof terminate at a point approximately three-fourths of the distance from the mid-point of the said

2

narrow area to the said elastic band, and a shirt tab secured to each of said side portions near said elastic band in said waist portion.

A further object is to provide in an infant's pants, a crotch portion comprising, an outer layer of water repellent cloth, an inner layer of water-repellent cloth, and an intermediate layer of difficult to stretch water repellent material with said layers being joined together by stitching.

Still a further object is to provide in an infant's pants having a body portion with leg cut-out portions, a shirt tab secured to each of the opposite sides of said body portion.

Another object is to provide in an infant's pants having a body portion with leg cut-out portions, a shirt tab secured to each of the opposite sides of said body portion, three crotch portions joined together by stitching, the inner one of said crotch portions being made of water repellent cloth, the intermediate crotch portion being made of a difficult to stretch water repellent material, and the outer crotch portion being made of a layer of water repellent cloth.

Other and further objects and advantages of the present invention will be apparent from the following description thereof.

Referring now to the drawing wherein like numerals refer to the same or corresponding parts throughout the several views:

Figure 1 is a perspective view showing the infant's pants embodying the features of the present invention as being worn by an infant with a part of the infant's shirt being broken away to show the attachment of the shirt tab to the inner tab of the infant's shirt;

Figure 2 is an enlarged detail showing how a shirt tab of the infant's pants is attached to the tab on the inner portion of the infant's shirt;

Figure 3 is a rear view of the infant's pants as shown in Figure 1;

Figure 4 is a side elevation of the pants shown in Figure 3;

Figure 5 is a sectional view taken along the line 5—5 of Figure 3 in the direction of the arrows;

Figure 6 is a sectional detail showing the pinning of the diaper tab of the infant's garment to the tab on the lower inside of the infant's shirt;

Figure 7 is a plan view showing the manner in which the crotch portions are laid out prior to assembly of the infant's pants; and

Figure 8 is a side elevation of the cloth blanks shown in Figure 7 showing the position of the several crotch portions.

Referring now to the drawing, and more particularly to Figures 7 and 8, the infant's pants embodying the features of the present invention include an outer layer of water repellent knit cotton indicated by the numeral 20, an intermediate layer of difficult to stretch or relatively non-stretchable water repellent material, such as flannelette, treated to repel water, indicated by the numeral 21, and an inner layer of water repellent knit cotton being indicated by the numeral 22.

As shown in Figure 7, each crotch portion of the infant's pants is similar in size and shape and comprises a narrow area 23 and two fan-shaped areas 24 and 25 extending therefrom, with the outermost point 24a of the fan-shaped area 24 terminating at a point which is approximately three-fourths of the distance from the midpoint of the narrow area 23 to the terminal point of the outer layer 20. The outermost point 25a of the fan-shaped area 25 likewise terminates at a point which is approximately three-fourths the distance from the midpoint of the narrow area 23 of the crotch portion to the other terminal point or free edge of the outer layer 20.

It is to be understood that each of the crotch portions of layers 20, 21, and 22 are preferably similar in size and shape, and each is provided with leg cut-out portions 26 and 27, on opposite sides thereof to provide openings for the infant's legs when the garment is in use, as shown in Figure 1 of the drawing.

In the assembly of the infant's garment, the various blanks as shown in Figures 7 and 8 of the drawing are

suitable folded and stitched with suitable stitching 28 so as to hold the three crotch portions firmly in place.

Likewise, suitable stitching 29 and 30 is used for the leg openings 26 and 27 to hold the three layers of cloth firmly in place.

As shown in Figure 4 of the drawing, the opposite side portions of the infant's pants are suitably joined together by means of stitching 31, it being understood that the stitching is similar for the front and rear of the infant's garment.

As the particular stitching employed does not per se comprise a part of the present invention, it is to be understood that any suitable stitching may be employed to join together the various layers of the cloth which make up the infant's garment embodying the principles or features of the present invention.

The numeral 32 generally refers to the waist area of the infant's garment, and there is provided an elastic waistband 33 which is suitably sewn into the free end of the waist portion 32 so as to provide the pants with sufficient resiliency to stay on the infant when in use.

An important feature of the present invention is the provision of shirt tabs 34 and 35 which are sewn, or otherwise secured to the side portions or areas of the infant's garment. These shirt tabs 34 and 35 are employed in securing the infant's pants to tabs on the inside of the lower portion of the infant's shirt S. For example, as shown in Figures 1, 2 and 6 of the drawing, shirt tab 34 is attached to the piece of cloth 34a which is disposed on the inside of the shirt S, the attachment being made through the means of a safety pin P.

Attention is directed to the fact that an important feature of the present invention is the employment of an intermediate layer of difficult to stretch flannelette, or like material, which has been treated with a water repellent composition. The purpose of the flannelette is to hold the two layers of water repellent knit goods in tight position. The difficult to stretch flannelette will prevent the small openings between the fibers of the knit goods from stretching and enlarging to such an extent that some wetness would seep through. The intermediate flannelette layer is positioned in the crotch area in such a manner as to repel the full strength of the baby's urine and to preclude the urine from travelling beyond the crotch area.

Another important feature of the present invention is the employment of the intermediate flannelette layer which is sewn into the leg openings of the baby's pants in such a manner that it will prevent the leg openings from stretching completely out of fit or out of shape after the baby's pants have been washed a few times. All knit garments are subject to easily stretching after washing which is not so with the pants of the present invention.

Various modifications of the present invention will be apparent to those skilled in the art without departure from the spirit thereof and it is therefore desired to be limited only by the scope of the appended claims.

What I claim is:

1. An infant's pants comprising, a one-piece outer layer of water repellent cloth, said outer layer of water repellent cloth consisting of a waist portion provided with an elastic band, side portions, and a crotch portion with oppositely disposed leg cut-out portions; an inner layer of water repellent material to provide a second crotch portion similar

in size and shape to said first mentioned crotch portion; an intermediate layer of difficult to stretch water repellent material to provide a third crotch portion similar in size and shape to said above mentioned crotch portions, said crotch portions being joined together by stitching, and a shirt tab secured to each of said side portions.

2. An infant's pants comprising, a one-piece outer layer of water repellent cloth, said outer layer of water repellent cloth consisting of a waist portion provided with an elastic band, side portions, and a crotch portion with oppositely disposed leg cut-out portions; an inner layer of water repellent material to provide a second crotch portion similar in size and shape to said first mentioned crotch portion; an intermediate layer of difficult to stretch water repellent material to provide a third crotch portion similar in size and shape to said above mentioned crotch portions, said crotch portions being joined together by stitching, each of said crotch portions including a narrow area and two fan-shaped areas each extending therefrom to have a portion thereof terminate at a point approximately three-fourths of the distance from the mid-point of the said narrow area to the said elastic band, and a shirt tab secured to each of said side portions near said elastic band in said waist portion.

3. An infant's pants comprising, a one-piece outer layer of water repellent knit cotton, said outer layer of water repellent knit cotton consisting of a waist portion provided with an elastic band, side portions, and a crotch portion with oppositely disposed leg cut-out portions; an inner layer of water repellent knit cotton material to provide a second crotch portion similar in size and shape to said first mentioned crotch portion; an intermediate layer of water repellent flannelette to provide a third crotch portion similar in size and shape to said above mentioned crotch portions; said crotch portions being joined together by stitching, each of said crotch portions including a narrow area and two fan-shaped areas each extending therefrom to have a portion thereof terminate at a point approximately three-fourths of the distance from the mid-point of the said narrow area to the said elastic band, and a shirt tab secured to each of said side portions near said elastic band in said waist portion.

4. An infant's pants comprising, a one-piece outer layer of cloth treated with a water repellent composition; said outer layer of water repellent cloth being made from a cloth blank and including a waist portion, opposite side portions and a crotch portion with oppositely disposed leg cut-out portions; a separate one-piece inner layer of water repellent cloth material comprising a second crotch portion substantially similar in size and shape to said first mentioned crotch portion; a separate one-piece intermediate layer of difficult to stretch water repellent cloth material comprising a third crotch portion substantially similar in size and shape to said above mentioned crotch portions; and said crotch portions and the side portions of said outer layer of cloth being joined together by stitching.
